UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

METHOD OF RECORDING AND REPRODUCING SOUND.

No Drawing. Application filed November 11, 1922, Serial No. 600,429, and in Germany November 11, 1921.

In the use of the method heretofore employed for recording and reproducing sound, the same arrangement must be used for reproducing the whole sound intensity 5 as well as the sound rhythm. The recording must, therefore, be effected at a very great intensity so that, during the reproduction, the stylus may perform the whole sound work. The stylus must undergo large 10 movements to follow the deep grooves of the record, and the stylus encounters very great frictional resistances. These frictional resistances and the strong movements of the stylus cause in turn strong side-tones resulting 15 from the engagement of the stylus with the record, which may be in the form of a disc, roll, etc. The pressure of the stylus on the disc or other record results in a further technical difficulty in that the record must 20 be hardened by means of the admixture of resinous substances and the like. Such hardening of the record causes the frictional and side-tones to be further increased. These noises due to friction between the 25 stylus and the record constitute the main short-coming of the present day acoustical apparatus. Their cause is not solely in the disc or other record but also in the sound box.

30 In accordance with the present invention, such noises are materially reduced by separating the functions of the stylus in such a manner that its acoustical work is materially lessened. To this end, when the record is 35 made, the stylus is caused to make only slight movements, such movements being so small that the resultant grooves are insufficient for audibly reproducing the sound intensity. The function of the grooves is only 40 to reproduce the form of the acoustical curve and not to produce the full intensity of the sound. During reproduction, the shallow grooves offer less frictional resistance to the stylus and the stylus performs a 45 much slighter movement. The reproducing sound box system may also be materially simplified. Furthermore it is no longer necessary to add hardening substances to the material composing the record disk. Electrical 50 amplifying arrangements are provided for producing sound of the desired intensity. The sound work of the stylus acts on a microphone arrangement—e. g. a microphone

provided on the reproducer diaphragm, the microphone currents being amplified in the 55 usual manner and transmitted at any desired strength to the horn of the sound reproducing apparatus.

The invention is applicable to use in connection with phonographs for reducing the 60 scraping noise caused by the travel of the stylus over the record and to polygraphs and similar writing machines, particularly when used with high speed printing telegraph apparatus. In fact, my invention is applicable 65 to any apparatus which makes use of recording and reproducing by means of a stylus on a blank record.

Having described my invention, what I 70 claim is:

1. A method of recording and reproducing sound which consists in producing on a record a shallow groove having the form of an acoustical curve, reproducing the sound at low amplitude requiring less energy than 75 is necessary to produce audible sounds by means of a stylus, and electrically amplifying the sound to bring it up to normal intensity.

2. A method of recording and reproducing sound, which consists in forming an acoustical curve on a record by means of a stylus, causing the record during the recording to be only slightly affected by the stylus so that the acoustical curve formed on the 85 record is insufficient for the reproduction of audible sound, reproducing the sound at low amplitude by means of a stylus, and electrically amplifying the sound to bring it up to 90 normal intensity.

3. A method of recording and reproducing sound which consists in operating on a record with a stylus to produce a groove having the form of an acoustical curve and being too shallow to enable direct reproduction of the sound at audible intensity, mechanically reproducing the sound at low amplitude and electrically amplifying the sound.

4. A method of recording and reproducing sound which consists in recording on a blank record by means of a stylus a sound groove by imparting just sufficient energy to record the acoustical curve, and then reproducing said sound by taking an inaudible 105 degree of energy from said record and suit-

ably amplifying said energy by a suitable amplifier.

5. A method of recording sound which consists in recording on a blank record by means of a stylus sound undulations of an inaudible degree of amplitude.

6. A method of recording sound which consists in recording on a blank record by means of a stylus sound undulations of just

sufficient amplitude to accurately record an 10 inaudible form of the sound wave.

7. A method of recording sound which consists in recording on a blank record by means of a stylus mechanism sound undulations of such amplitude as to be inaudible 15 if reproduced directly by means of said stylus mechanism.

DR. ALEXANDER MEISSNER.
